UNITED STATES PATENT OFFICE.

SIEGFRIED ROSENZWEIG, OF NEW YORK, N. Y.

CENTRIFUGAL GOVERNOR FOR STEAM-ENGINES.

1,239,828.

Specification of Letters Patent. Patented Sept. 11, 1917.

Application filed April 18, 1917. Serial No. 162,848.

To all whom it may concern:

Be it known that I, SIEGFRIED ROSENZWEIG, a citizen of the United States, residing in New York city, in the county and State of New York, have invented a certain new and useful Improvement in Centrifugal Governors for Steam-Engines, of which the following is a specification.

My invention relates to that class of centrifugal speed governors for steam engines, in which there are two pendulums, pivotally connected to the governor body—which is keyed to and revolves with the engine shaft—and combined with a longitudinally 15 curved flexible spring strip having one end immediately or immediately attached to the governor body, and the other or free end connected to the pendulums and subjected to the centrifugal forces thereof, the stress or 20 tension of the spring resisting the centrifugal forces of the pendulums, and the speed of the engine, for a given weight of pendulums, depending upon the resistant force of the spring—the speed of the engine increasing 25 with the increase in the initial stress or tension of the spring, and vice versa.

The object of my invention is to produce a simple and efficient governor of this type in which the speed adjustment can readily 30 be effected by hand whether the governor be at rest or in motion, and in which the working length of the spring will be automatically varied for the purpose of varying its stiffness, conformably to the changes in the 35 stress or tension of the spring effected through the intermediary of said hand-operated speed-adjustment means. I am aware that, in case of the adjustment of the stress or tension of said spring in the direction of 40 increasing said stress or tension, with a view to increase the speed of the engine, it has been proposed to provide means by which the effective length of spring may, in these circumstances, be shortened with a view to 45 enhance its stiffness as desired, and this I do not broadly claim. My invention resides in the combination and arrangement of instrumentalities, for the purposes herein before stated, illustrated in the accompanying drawings, to which I shall now refer for a better understanding of the improvement. I shall first describe the structure embodying 50 the improvement in connection with said drawings, and will then point out in

the claims those features thereof which I believe to be new and of my own invention.

In the drawings:

Figure 1 is a vertical axial section partly in elevation of the governor and so much of the parts with which it is immediately associated as required for the purposes of explanation.

Fig. 2 is a side elevation of the governor looking at it from the left, the governor shaft and governor casing being in section.

Fig. 3 is a like elevation of the governor looking at it from the right, with the governor casing removed, and the governor shaft in section.

Fig. 4 is a section on line 4—4 Fig. 3.

M is the governor shaft and N is the body of the governor keyed as usual to, and revolving with, the said shaft. At diametrically opposite positions on the governor body are located pendulums A, B, connected to the governor body by pivot pins C, D, respectively. From the hubs of the pendulums extend inwardly arms m shown in Fig. 1 and in dotted line in Fig. 2, in the outer ends of which are guideways n for sliding blocks n' rotatably mounted on pins p, the ends of which are journaled between disks q, q', connected to move in unison and revolvably mounted on the shaft M. From the outer face of the larger disk q projects an eccentric pin r, carrying in its outer end a swivel block s which is mounted and can slide in the slot t in the shiftable eccentric v which is connected to and adapted to operate the valve gear of the engine and is mounted on the smaller eccentric w which is fixed to and revolves with the engine shaft. The movement of the pendulums on their pivots will occasion corresponding movement of their operating arms m which, through the described mechanism intervening between them and the shiftable valve gear eccentric v, will shift the latter on its operating fixed eccentric w to regulate the cut-off in the usual manner. Thus far there is nothing new in the governor.

F is a flat longitudinally curved spring strip, one end of which is hooked over or otherwise attached to an inwardly extending projection E cast on or otherwise attached to the hub of one of the pendulums—in this instance the pendulum B. The spring then is passed, in an approximately

circular path, and in a direction opposite to the pull which the pendulum projection E exercises on it during the outward swing of the pendulums, up, over and down on the 5 other side of the governor shaft M where its other end is bolted or otherwise suitably secured to the free end of a swinging arm G. This arm is eccentrically pivoted to the governor body at g; it thence extends in a 10 curved path around and partly encircling the engine shaft, so as to bring its free end (to which one end of the spring is attached as already indicated) on the other side of the engine shaft from the pivot g, opposite 15 to and at a suitable distance from the projection E to which the other end of the spring is secured. By swinging the arm G toward or away from the projection E, the stress of the spring will be correspondingly 20 varied, as will be understood without further explanation. The eccentric mounting of the arm G with reference to the governor shaft enhances the efficiency of the device, inasmuch as for a given length of movement 25 of the arm toward the point E where the other end of the spring is located, a greater curvature of the spring will result than would be the case were said arm mounted to move concentrically with the governor shaft. Besides which the said arrangement 30 permits of a very simple and effective means of adjusting the stress of the spring, whether the governor be in motion or at rest.

35 Said means comprises a tubular thimble H mounted on and fitting the governor shaft and adapted to rotate therewith, and having a wedge or tapered front end h which enters between the governor shaft and the 40 portion of the swinging spring adjusting arm G which adjoins and partly encircles the governor shaft, said thimble when its tapered or wedge shaped end is pushed forward or advanced between the arm G and the 45 governor shaft acting to swing the said arm outwardly or away from the governor shaft, with the effect of moving the free end of the arm nearer to the point E, and thus correspondingly increasing the stress of the 50 spring. On the inner face of the arm G at the point where it contacts with the beveled face of the thimble H is a projecting bearing lug g' suitably formed to contact with the beveled end of the thimble and to 55 permit the longitudinal movement of the latter without cramping or undue friction. The thimble H is connected to an annular coupling ring I by an annular tongue and groove connection (the tongue i on the 60 coupling and the groove h' in the thimble), which will permit the thimble to revolve freely with the governor shaft independently of the coupling ring. The coupling ring extends out through the side of the casting and is fixed to an adjusting sleeve

J which encircles while not contacting with, the governor shaft and is externally screw-threaded to engage the correspondingly internally screw-threaded housing K attached to the adjoining governor shaft 70 bearing K'. Anti-friction washers j' or other suitable means for reducing friction and wear are interposed between the adjoining ends of the adjusting sleeve and the thimble. Upon the adjusting sleeve 75 J is keyed a hand wheel L for rotating it, and thus moving the beveled thimble lengthwise of the governor shaft according to the direction of rotation of the adjoining sleeve. 80

By turning the hand wheel in a direction to advance the tapered thimble H toward the governor body, between the arm G and the governor shaft, the arm will be swung outwardly, thus causing the free end of the 85 said arm to which one end of the spring is attached to be moved toward the projection E to which the other end of the spring is attached, which effects an increase in the 90 stress or tension of the spring with consequent increase in the speed of the engine. Movement of the hand wheel in the opposite direction will produce the contrary effect.

While the arrangement thus far described is very effective to vary the engine speed 95 within certain limits, yet excessive stress on the spring may cause the governor to become what is termed unstable, and lose its speed control capacity. It has been found that this defect can be remedied by providing means whereby the spring may be made stiffer when increasing its stress. Inasmuch as the increase in stiffness of the spring can be secured by shortening its working length, I have provided for this purpose a simple 100 but effective device whereby the working length of the spring is automatically varied to conform to the stress or tension of the spring, consisting of an arm R cast in one with, or otherwise suitably fastened tight to, the body of the governor—preferably the hub of the governor body as shown in Fig. 3—and extending outwardly therefrom until its outer end meets and bears against the under face of the spring at any given distance from the point of attachment of the spring to the swinging arm G. The stress 110 of the spring will hold it tight down upon the end of arm R which furnishes a bearing that in effect determines the effective working length, or length of the effective working portion, of the spring—that portion of the length of the spring which intervenes between its bearing at R, and its point of attachment to the arm G being ineffective 115 for that purpose. When the arm G draws the spring over the fixed bearing point R, and in a direction to increase its stress, the distance between R, the fixed point, and the movable point G will be correspondingly in- 120 130

creased, with a like increase in the idle length of the spring between the points R and G, and decrease in the active or effective working length of the spring and conse-

- 5 quent increase in its stiffness. The bearing point on the arm R over which the spring passes may be provided with a roller R' to reduce friction. The arm R being rigidly secured to the governor body always occupies 10 the same position thereon notwithstanding the pressure of the spring upon it which tends to pull it in the direction of the longitudinal movement of the spring that takes place in changing the stress or tension of 15 the same, thus permitting the ready and accurate adjustment of the spring whether the governor be in motion or at rest.

Having described my improvement and the best way now known to me of carrying 20 the same into practical effect, I would state in conclusion that I do not limit myself narrowly to the particular structural details herein before shown and described, since manifestly the same can be varied to some 25 extent without departure from the spirit of my invention: But what I claim as new and desire to secure by Letters Patent is:

1. In a steam engine governor, the combination with the governor shaft, the governor 30 body revolving therewith and the centrifugal pendulums pivoted to the governor body at diametrically opposite points on the same; of a swinging arm pivoted to the governor body eccentrically with reference 35 to the governor shaft and thence extending crosswise of said shaft in a curved path around and partly encircling the same so as to bring the free end of the arm on the other side of the shaft from the point at 40 which said arm is pivoted to the governor body; a spring extending in a curved path around the governor shaft, secured at one end to the free end of the eccentrically pivoted arm, and at its other end to that one 45 of the pendulums whose pivot adjoins the free end of said arm; and adjusting means for moving said eccentrically pivoted arm

in one direction or the other to vary the stress of the spring as desired and for holding the thus-moved arm in its adjusted position. 50

2. In a steam engine governor, the combination with the governor shaft, the governor body revolving therewith, and the centrifugal pendulums pivoted to the governor body at diametrically opposite points on the same; of a swinging arm pivoted to the governor body eccentrically with reference to the governor shaft and thence extending crosswise of said shaft in a curved path 60 around and partly encircling the same, so as to bring the free end of the arm on the other side of the shaft from the point at which said arm is pivoted to the governor body; a spring extending in a curved path 65 around the governor shaft, secured at one end to the free end of the eccentrically pivoted arm, and at its other end to that one of the pendulums whose pivot adjoins the free end of said arm; a tubular wedge-like 70 thimble interposed between opposed faces of the eccentrically pivoted arm and the governor shaft, mounted on the latter, and slideable lengthwise of the same to vary the interval between said shaft and arm; and 75 manually operable means, operatively coupled to said wedge-like thimble for thus moving it and holding it in its adjusted position.

3. In combination with the elements specified in claim 1, the arm R rigidly secured to the governor body and bearing at its outer end against the under face of the curved spring at a predetermined distance in advance of the point of attachment of said 80 spring to the free end of the eccentrically pivoted swinging arm, substantially as and for the purposes herein before set forth. 85

In testimony whereof, I affix my signature in presence of two witnesses.

SIEGFRIED ROSENZWEIG.
